2 Claims. (Cl. 137—139)

This invention relates to a method of and means for the electromagnetic regulation of the output of compressors.

Our U. S. Patent No. 2,035,963 discloses an automatic load regulator for a piston compressor, in which, by the pole reversal of the electromagnets by means of magnet coils of different polarity disposed in a row, the troublesome residual magnetism of the electromagnets is eliminated. At the same time the play of the magnets is accurately attuned to the individual phases of movement of the suction valve. The play of the suction valve of a compressor the regulating of which is effected by keeping the suction valve open for a greater or less part of the pressure stroke, is as follows: The suction valve is open throughout the entire suction stroke, also open during a portion of the pressure stroke corresponding to the desired reduction of output, and closed during the remainder of the pressure or delivery stroke. In the method forming the subject matter of the above-mentioned patent there is provided, in accordance with this valve play, alternate activation and neutralization of the electromagnets, with reversal of polarity after each neutralization. This arrangement necessitates a complicated system of connections.

The present invention provides a method of electromagnetic regulation of the output of compressors in which the troublesome residual magnetism of the magnets is likewise eliminated. According to the invention use is made of the difference in magnitude between the attracting and retaining forces of the open and closed magnetic circuit, respectively, on the one hand, and the pressure forces bearing upon the open and closed suction valve, respectively, on the other hand. The force of the magnet is arranged to be such that it is indeed capable of holding the lifted valve open against the action of the forces tending to close it at the commencement of the pressure stroke, that is to say against the force of the valve springs and of the delivery pressure. When once the suction valve is closed, however, so that the rapidly increasing pressure in the cylinder of the compressor bears upon it, even the excited magnet is not capable of lifting it from its seating. The invention thus consists in an arrangement by which, in a preferred embodiment, during the pressure stroke, at the moment of the intended closing of the suction valve, a pole reversal of the magnet governing the suction valve is effected, which enables the valve to close in response to the action of its normal closing forces, whereas on the other

hand for the remainder of the pressure stroke the force exerted by the excited magnet upon the closed suction valve is not capable of overcoming the rapidly increasing pressure in the cylinder, which takes effect against the opposite side of the valve. In this connection it is even possible, during a complete revolution of the compressor, to effect two pole reversals displaced 180° relatively to each other, of which one always falls within the suction stroke and thus produces no result with regard to the regulation of this end of the cylinder. If however the valve controlling magnets at the front and at the rear ends be connected together, then the ineffective one of these pole reversals (which occurs within the suction stroke) at one end of the cylinder brings about closing of the suction valve at the other end of the cylinder, since the suction and pressure periods in front of and behind the piston are offset 180° relatively to each other.

Two forms of construction embodying the invention are shown, by way of example, in the accompanying drawing, in which:

Fig. 1 shows diagrammatically an arrangement of connections in which only one valve controlling magnet is provided.

Fig. 2 is a second diagram for an arrangement embodying two coils.

The rotating disc 11, which is driven for example at half the speed of the compressor, is provided with two semi-annular contacts 12 and 13 which are displaced 180° relatively to each other, and one of which, by means of suitably positioned sliding contacts 14 and 15 is at all times connected to the positive pole and the other of which by sliding contacts 16 and 17 is at all times connected to the negative pole of a source of current 28. Upon a distributing bar or bridge 18 which is normally fixed in position there are provided two pairs of relatively displaced contacts 19, 20 and 21, 22 the spacing of which is equal to the radial displacement of the two semi-annular contacts from each other. Each two adjacent contacts 19, 20 and 21, 22, respectively, pertaining to the rotary contact bridge 18, and associated with different contact rings 12, 13, are connected together and each pair is connected to one end of the magnet coil 23. At each revolution of the contact disc 11 the direction of the current flowing through the coil thus changes twice. This means—provided the contact disc 11 rotates at half the speed of the compressor—a single pole reversal of the magnet 23 during one revolution of the compressor. By adjustment of the contact bridge 18 in its orientation

tation about the axis of the disc 11, which can be effected by hand as shown at 40, 41, or by any automatic means for imparting an impulse, this alteration in the direction of flow of the current, which corresponds each time to a pole reversal of the magnet, is caused to take place at the desired point in the pressure stroke of the piston.

The cylinder 30 has the piston 31, and also has a suction valve 32 held normally closed by a spring 33 acting on lug 37 carried by valve stem 35 and also acting against abutment 38. Electromagnet 23 has pivotally mounted armature 34 pivotally connected to valve stem 35. Crank disc 36 drives piston 31 and also by shaft 39 drives rotating disc 11. The distributing bar or bridge 18 is freely journalled on shaft 39 and can be adjusted into any desired position by adjusting means 40, 41.

The rotating disc 11 may however also be driven at the same speed as the compressor. In this case two pole reversals of the magnet 23 take place at each complete revolution of the compressor, these pole reversals being displaced 180° relatively to each other. Thus if the one falls within the pressure stroke the other necessarily falls within the suction stroke. Since during this latter phase the valve is held open in any case by the force of the flowing medium this second pole reversal has no effect whatever upon the valve play. This form of construction has incidentally the advantage that the magnets for the controlling of the suction valves in front of and behind the piston can be connected together. Since the suction and pressure periods on both sides of the piston are displaced 180° relatively to each other each pole reversal which takes place without effect upon the one suction valve brings about a closing of the suction valve on the other side of the cylinder. With the arrangement of connections shown in Fig. 1 only one magnet coil 23 is required. But there are four points of interruption.

The same result as regards the controlling effect can be obtained with the form of construction outlined in Fig. 2, in which two coils 24 and 25 are provided for each valve. The connection 26 between these two coils is connected for example, through ground or conducting mass, to the one pole of the current source, while the two other ends 27 and 28 are alternately brought into connection with the second pole of the current source by means of the contact disc 11 in conjunction with the adjustable contact bridge 18. With this arrangement there are thus two or more pairs of coils 24, 25, but only two points of interruption.

We claim:

1. In the operation of an electromagnetically controlled valve actuating mechanism for a fluid piston compressor having a suction valve normally closed by a resilient force and further having an electromagnet with a single actuating winding adapted when energized to apply to said valve a pushing force tending to open the same, the method of electromagnetically regulating the compressor load which consists in applying to the magnetic circuit of said electromagnet at the beginning of the compression stroke of said piston a magnetomotive force in one direction of magnitude sufficient to produce an opposing attractive force greater than said normally closing resilient force and then maintain said valve open, reversing said magnetomotive force at an instant intermediate of the compression stroke of said piston, and maintaining the pushing force exerted by said electromagnet on said valve at all times less than the fluid pressure exerted against said valve at the end of its compression stroke with said valve closed.

2. In the operation of an electromagnetically controlled valve actuating mechanism for a fluid piston compressor having a suction valve normally closed by a resilient force and further having an electromagnet with a single actuating winding adapted when energized to apply to said valve a pushing force tending to open the same, the method of electromagnetically regulating the compressor load which consists in causing said electromagnet at the beginning of the compression stroke of said piston to produce an opposing attractive force greater than said normally closing resilient force and thereby maintain said valve open, then at an instant intermediate of the compression stroke of said piston reducing to zero and reversing in direction the magnetomotive force applied to the magnetic circuit of said electromagnet and thereby reducing to zero the opposing attractive force produced by said electromagnet and thereby closing said valve, and then at a subsequent instant intermediate of said compression stroke and continuing to the end of the compression stroke causing said electromagnet to produce an opposing attractive force less than the resilient and pressure forces then tending to keep said valve closed but sufficient to overcome said resilient force alone.
